MOLDING JACKET

Russell J. Hines, Lakewood, Ohio, assignor to The Hines Flask Co., Cleveland, Ohio, a corporation of Ohio

Application November 13, 1948, Serial No. 149,615

Term of patent 14 years

(Cl. D54—8)

To all whom it may concern:

Be it known that I, Russell J. Hines, a citizen of the United States, residing at Lakewood, in the county of Cuyahoga and State of Ohio, have invented a new, original, and ornamental Design for a Molding Jacket, of which the following is a specification, reference being had to the accompanying drawing, forming part thereof.

Fig. 1 is a perspective view of a molding jacket embodying my new design; Fig. 2 is a side view; the sides not shown are the same as the sides shown.

I claim:

The ornamental design for a molding jacket, as shown and described.

RUSSELL J. HINES.
